UNITED STATES PATENT OFFICE.

JAMES B. JOHNSON, OF SPRINGFIELD, MASSACHUSETTS, ASSIGNOR TO SPRINGFIELD METAL FURRING COMPANY, OF SPRINGFIELD, MASSACHUSETTS, A CORPORATION.

METALLIC BUILDING CONSTRUCTION.

1,159,039.

Specification of Letters Patent.

Patented Nov. 2, 1915.

Application filed February 1, 1915. Serial No. 5,489.

To all whom it may concern:

Be it known that I, JAMES B. JOHNSON, a citizen of the United States, residing at Springfield, Massachusetts, have invented 5 certain new and useful Improvements in Metallic Building Construction, of which the following is a specification.

My present invention relates to improvements in metallic building construction and 10 is applicable in connection with constructions, such as shown in Letters Patent of the United States granted to me on the 20th day of August, 1912, #1,036,522 and January 13, 1914, No. 1,084,580.

15 The invention has among others for its objects to provide a simple and economical wall construction in which the parts may be readily assembled and firmly and durably held together.

20 The invention includes the novel features of construction and arrangement and combination of parts hereinafter described and particularly defined by the appended claims.

In order that my improved construction 25 may be clearly understood, reference is had to the accompanying drawing in which;

Figure 1 is a side elevation of such a wall construction. Figs. 2 and 3 are sections taken respectively on lines 2—2 and 3—3 of 30 Fig. 1. Figs. 4 and 5 are views similar to Fig. 1 showing the construction as it would appear in an outside wall. Fig. 6 is a detail view of a further modification.

In this drawing, the letter A designates 35 a vertical stud or I-beam designed to support at its edges furring strips B, and connected at its ends to the main supporting or I-beams C.

I prefer to construct the stud A of two 40 channel members secured together by means such as bolts or rivets and having flanges first turned outwardly away from each other as indicated at a, a and then doubled back as indicated at a', a' forming grooves 45 or channels a², a² to receive the opposite edges b, b of the furring strips B.

In order to connect the stud A to the beam C I provide a substantially U-shaped or channel member D having laterally extending flanges d which are embraced by the 50 channeled edges e of a two-part clamping member E, the parts of which are held together in clamping position by extending

between the walls of the stud A and being engaged by the bolts or rivets a³.

Within the channel member D is placed a furring strip B' of channel form which is held therein by having its edges engaged by the turned over edges d of the strip or bar D. The channel of the member D is of 60 greater height than the furring strip so as to have a space d' and a portion of the crown or top of the strip D is cut away as indicated at d², to allow one wall or flange of the main beam C to rest directly against 65 the top or crown of the furring strip. The parts are locked in this position by wedges F which are driven into the spaces d' in the ends of the member D, the ends of these wedges overlapping the flanges c of the 70 beam C.

The wedges may be locked in position by means of lugs or tongues b' which may be formed by slitting portions of the furring strip to provide tongues which may be bent 75 up after the wedges are driven into place.

It will be understood that as embodied in an outside wall the flanged beam C would be held by a single wedge as shown in Figs. 4 and 5 the opposite flange being held by 80 the overturned clip or portion b². In such outside construction the portion D may be made to overhang the flange as indicated at D' in Fig. 6 and a metal wedge or key F' used, these parts D' and F' being of less 85 height than the parts D and F of Figs. 4 and 5.

I claim:

1. In a wall construction, a stud, a channel member extending across one edge thereof and having a cut away portion, means for connecting the said channel member to said stud, a channel shaped furring strip within said channel member, a flanged beam seated in a cut away portion of the channel member and a wedge inserted in the space between said channel member and furring strip and overlapping a flange of said beam, substantially as described.

2. In a wall construction a stud, a channel member extending across one edge thereof, means for connecting said channel member to said stud, a channel-shaped furring strip within said channel member and of less depth than said channel member, said channel member having a cut-away portion, a

2
flanged beam seated in said cut away portion, a wedge in the space between said channel member and furring strip and overlapping a flange of said flanged beam, and 5 means for locking said wedge in position.

3. In a wall construction a stud, a holding clip carried at the end thereof having opposing channels, a channel member having oppositely extended flanges seated in said 10 channels, said flanges having internal grooves, a channel-shaped furring strip within said channel member and having lateral flanges seated in said grooves, said furring strip being of less depth than said 15 channel member and said channel member having a portion of its crown cut away, a flanged beam seated in said cutaway portion, and a wedge inserted in said channel member and overlapping a flange of said 20 last named beam.

4. In a wall construction, a stud, a holding clip carried at the end thereof having

opposing channels, a channel member having oppositely extended flanges seated in said channels, said flanges having internal 25 grooves, a channel-shaped furring strip within said channel member and having lateral flanges seated in said grooves, said furring strip being of less depth than said channel member and said channel member having a portion of its crown cut away, a flanged beam seated in said cutaway portion, and a wedge inserted in said channel member and overlapping a flange of said last named beam, and an integral bendable 30 lug on said furring strip for holding said 35 wedge in place.

In testimony whereof, I affix my signature in presence of two witnesses.

JAMES B. JOHNSON.

Witnesses:

LINNA M. BOYLE,
OPHELIA GRACE BRUNELLE.
